CLAIM

The ornamental design for a frame assembly cover for a patient interface, as shown and described.

DESCRIPTION

FIG. 1 is a top plan view of a frame assembly cover for a patient interface showing our new design;

FIG. 2 is a front elevational view thereof;

FIG. 3 is a perspective thereof;

FIG. 4 is a right side elevational view thereof, the left side elevational view being a mirror image thereof;

FIG. 5 is an alternate perspective view thereof; and,

FIG. 6 is a rear elevational view thereof.

The broken lines in the drawings illustrate portions of the frame assembly cover for a patient interface that form no part of the claimed design.
